UNITED STATES PATENT OFFICE.

THOMAS ROBERT BEGGS, OF NEW YORK, N. Y., ASSIGNOR TO THE BEGGS ENGINEERING COMPANY, INCORPORATED, OF HARTFORD, CONNECTICUT.

FLUSHING DEVICE.

Application filed June 30, 1920. Serial No. 393,092.

To all whom it may concern:

Be it known that I, THOMAS R. BEGGS, a citizen of the United States, residing at New York, in the county of New York and 5 State of New York, have invented a new and useful Flushing Device, of which the following is a specification.

This invention refers to a flushing device and its object is to provide a structure by 10 means of which a flow of water directly from a service pipe may be delivered to a toilet bowl without causing hammering and also avoiding the use of a flush tank.

This application is a continuation of my 15 application Serial No. 297,048 for a flushometer, filed May 14, 1919, in so far as the two applications contain common subject matter. In accordance with the invention there is provided a structure of small size 20 which, after being started, will automatically maintain the full initial flow of water for the full time for which the device is set, and the flushing valve will then close rapidly but will be checked just before becoming 25 seated in order to permit the bowl to refill.

The invention will be best understood from a consideration of the following detailed description taken in connection with the accompanying drawings forming part 30 of this specification, with the understanding, however, that the invention is not confined to any strict conformity with the showing in the drawings but may be changed and modified so long as such changes and modifications mark no material departure from the salient features of the invention as expressed in the appended claims.

In the drawings:

Fig. 1 is an elevation of the flushing device as viewed from one side.

Fig. 2 is an elevation of the flushing device taken from a point of view at substantially right angles to that of Fig. 1.

Fig. 3 is a vertical section on the line 3—3 45 of Fig. 2.

Fig. 4 is a section on the line 4—4 of Fig. 1.

Fig. 5 is a section, partly in elevation, of a portion of the casing.

Fig. 6 is a section at about 90 degrees to that of Fig. 5.

Fig. 7 is a plan view of the flushing device.

Fig. 8 is an inverted plan view of the upper portion of the flushing device removed 55 from the lower portion.

Referring to the drawings there is shown a body member 1 which may be in the form of a casting enclosing a chamber 2. This body member 1 has a socket 3 at one side to receive a service pipe, which latter is not shown in the drawings but may be considered as constituting a part of the service system of the house or other building in which the flushing device is installed. The top of the body member 1 is formed with an outstanding flange 4. The flange enters a socket or flange portion 5 of an upper or cover member 6 to which the body member is secured by means of screws 7 or in any other appropriate manner, and a diaphragm 8 of leather or other suitable material, forms a division wall between the upper and lower members of the casing. The diaphragm 8 forms the top wall of the chamber 2 and the bottom wall of another chamber 9 which latter is defined within the cover member 6. Uprising from the cover member 6 is a neck 10 with stepped walls 11, 12, 13 surmounted by a circumferential groove 14, with the walls 11, 12 and 13 and groove 14 gradually 80 increasing in diameter and finally terminating in a ledge 15 above which there is a tubular continuation 16 rising to an appropriate height and provided at the upper end with a screw cap 17 by which the tubular continuation or cylinder 16 is closed at the upper end in a water and air tight manner.

In the neck 10 there is located a hollow plug 18 formed exteriorly with stepped flanges 19, 20, 21 and 22 between each of which and a corresponding ledge 11, 12, 13 and 15 is a packing ring 23, so that the plug is encircled by a series of annular channels 24, 25 and 26. The plug 18 is provided with a longitudinal central port or passage 27 with which the several channels 24, 25 and 26 communicate through series of ports 28. The plug 18 is held in place in the neck 10 by means of the flanges 19 to 22 resting on the shoulders or ledges 11, 12, 13 and 15 and by a nut 29 screwed on to the smaller end of the plug which has a threaded extension 30 for the purpose.

The port or passage 27 is of even diameter throughout to house a piston or slide valve 31 provided with packing rings 32, 33 and 34 in a suitably spaced position so as to open and close the ports 28 as the slide valve or piston 31 is moved lengthwise of the port 27. Within the slide valve 31 is an 105 110

axial passage 35 opening through the upper end of the slide valve, where the latter is threaded, for the reception of a clamp nut 36 so arranged as to hold the packing rings 33 and 34 in place on the piston. Between the rings 33 and 34 is a spacer 37 with a port 38 therein and so arranged that when the slide valve 31 is in proper position communication is had between the groove 25, 10 the corresponding ports 28, the bore 35 of the slide valve 31 and the bore 27 of the plug 18, as shown in Fig. 3.

Within the cylinder 16 there is located a freely movable plunger 39 with a marginal packing cup or ring 40 held in place by a nut 41 whereby the plunger 39 may be moved lengthwise of the cylinder 16 without leakage of water past it, due to the presence of the packing 40.

20. The slide valve 31 has a screw-threaded extension 42^a entering its lower end and having a clamp nut 42 serving to hold the packing ring 32 thereto, and the slide valve is continued below the nut 42 and carries a ball 43 seated in a block 44, constituting a ball and socket joint of some flexibility, the block 44 being provided with an axially extended threaded stem 45. The block 44 engages the upper face of the diaphragm 8 and on the opposite or under face of the diaphragm there is a clamp plate 46, a gasket 47 and an internally threaded block 48 serving as a clamp nut to force the parts together, thus binding the block 44 and the 30 diaphragm 8 together. The stem 45 extends through and is guided by a spider 49 located in a pipe extension 50 of the body member 1, said extension 50 having terminal screw threads 51 by means of which the pipe 50 may be connected to a toilet bowl. The pipe extension 50 is entered by the block 48, which is concentric with the pipe 50 so that the outlet leading to the toilet bowl is constricted.

45. The end of the pipe 50 within the chamber 2 terminates in a valve seat 53 with which the gasket 47 engages when down thus closing communication between the chamber 2 and the pipe 50. In this position of the 50 parts, shown in Fig. 3, the slide valve 31 closes the lower end of the bore 27 except for ports 54 through the walls of the plug 18 below the nut 29. The bore 27 communicates through a set of ports 28 with the 55 channel 24, the passage 35 in the plunger 31 communicates through the port 38 and other ports 28 with the channel 25 and the packing ring 34 blocks the port 28 opening into the channel 26.

60. The channel 26 is in communication through a duct 55 with the chamber 2, the duct 55 being formed through an offset 56 outside of the upper casing member 6. This same upper casing member 6 is provided 65 with another offset 57 having an outlet

chamber 58 therein with which there communicates a duct 59 coming from the channel 25.

The offset 57 carries a plunger guide 60 in which there is mounted a plunger 61 having a rising tendency imparted to it by a spring 62. The plunger 61 is continued as a stem 61^a through the housing 60 into the chamber 9 where the plunger stem carries a laterally expanded head 63 in the path of which is another laterally expanded head 64 on the lower end of a rod 65 rising into a guide passage 66 formed in an offset 67 on one side of the neck 10 and cylinder 16, the offset 67 being conveniently formed by casting it in place. The stem 61^a carries a cup leather 61^b engaging the plunger head 61 and thereby preventing leakage.

The plunger guide 60, where it passes through the chamber 58, has holes or ports 58^a, and the plunger 61 has longitudinal ribs 60^a providing passageways for the water, between the plunger guide 60 and the plunger stem 61^a, so that when the plunger is depressed, the chambers 58 and 9 are in communication with each other through the ports 58^a and the spaces between the ribs 60^a. The plunger stem 61^a holds a washer 63^a against the head 63 to serve as a valve for the lower end of the plunger guide 60.

95. The rod 65 is of sufficient length to reach nearly to the top of the cylinder 16 through the passage 66 and near the bottom of said passage carries a piston or slidable valve 68 capable of moving between differently placed ports 69 and 70. A port 71 affords communication between passage 66 and the annular channel 24. At the upper end of the rod 65 there is secured a bracket 72 which may be conveniently clamped into place by a notched lock nut 73 permitting the free passage of water past it. The bracket 72 is provided with a finger 74 extending into the interior of the cylinder 16 and there carrying a set screw 75 to act as an adjustable abutment for the piston or plunger 39. Carried by the rod 65 is an elastic friction member 76 arranged to hold the rod 65 in adjusted positions but yielding to the engagement of the head 63 with the head 64 upon the depression of the plunger 61.

110. At one side of the cylinder 16 there is formed an offset boss 77 constituting a support for a hub 78 of a manipulating handle 79, the hub fitting snugly and freely on the boss and being there held by a suitable set screw 80, passing through a spacer sleeve 80^a which prevents binding of the hub 78 when the screw is firmly seated. In order to restrict the movement of the handle 79 the hub 78 is provided with a concealed groove 81 into which projects a stop screw 82 in the path of a pin or screw 83 carried by the hub within the groove 81. The hub 125

78 has a finger 84 projecting therefrom in position to engage the plunger 61 so that on manipulation of the lever or handle 79 the plunger 61 is actuated in a direction 5 against the spring 62 so as to cause the head 63 to engage and depress the head 64 and this correspondingly depresses the rod 65 and opens the passage 71, closes the port 69 and opens the port 70.

10 The chamber 58 in the boss 57 is connected by a duct 85, constituting an exhaust duct, with another duct 86 in the base of the upper section 6 of the casing. The duct 86 communicates through a passage 87 through

15 the diaphragm 8 where it is clamped between the two casing members 1 and 6 with another conduit 88 leading into the pipe 50 and so discharging into the flush bowl.

With the parts in the position shown in 20 Fig. 3 the flushing device, with the exception of the pipe 50, is full of water and water at service pressure occupies the chamber 2. The water at service pressure also flows by way of the duct 55 Fig. 5 to the 25 channel 14 and thence by another duct 89 in the neck 10 to a space or channel 90 Figs. 3 and 5 surrounding the nut 29 and the water finds its way into the chamber 9 by way of the port 69. The result is that the 30 chambers 2 and 9 contain water at service pressure and the differential pressure on the opposite sides of the diaphragm holds the valve 46 firmly on its seat. The slide valve 31 is consequently held in its lowermost position, as seen in Fig. 3, and the service pressure also is transmitted from chamber 9 through ports 54, and the lowermost ports 28 into channel 24, and thence through port 71 and passage 66, to the cylinder 16 above 35 the plunger 39. At this time, the lower part of the cylinder 16 below the plunger 39, is in communication through the bore 35, port 38, channel 25 and passage 59, with the chamber 58, which is always connected through ducts 85, 86, 87 and 88, with the outlet pipe 50.

When the handle 79 is manipulated to depress the plunger 61, and to simultaneously lower the rod 65 and valve 68, the latter 50 closes the port 69, thus relieving the pressure in chamber 9 as well as in the upper part of chamber 16, which has thus far been in communication with chamber 9. The diaphragm 8 is therefore immediately 55 raised by the pressure in chamber 2, while the chamber 9 is initially vented through the passages between the ribs 60^a and through the ports 58^a and chamber 58. As the diaphragm rises, it carries the slide 60 valve 31 upwardly until the packing ring 32 is above the ports 54 and the packing 33 is above the intermediate ports 28 leading into the channel 25 which is connected through the port 59 with the exhaust chamber 58. At the same time, packing ring 34

has uncovered the uppermost port 28 leading from the channel 26 so that pressure enters through passage 55, channel 26, port 38 and bore 35 underneath the plunger 39.

The plunger 61, as soon as the handle 79 is released, is returned to normal position by the spring 62, but the rod 65 and valve 68 remain depressed until restored by the operation of the plunger 39 as hereinafter explained. The chamber 9, however, continues to be vented through ports 70 and 71, channel 24, the lower two sets of ports 28, the channel 25, port 59 and exhaust chamber 58.

This condition prevails until the service water slowly entering through the bore 35 raises the plunger 39, until the latter striking the screw 75 raises the valve 68 again to the position shown in full lines in Fig. 4. Meanwhile the valve 45 is wide open and the bowl is being flushed. By adjusting the screw 75, the length of the travel of the plunger may be varied to thereby vary the duration of the flushing operation.

As soon as the valve 68 is raised, the uncovering of port 69 again restores pressure to the chamber 9. This again lowers the diaphragm 8, valve 46 and slide valve 31, until the ports 54 are uncovered. At the same time the lower part of chamber 16 beneath the plunger 39 is again vented through the bore 35, port 38, channel 25, port 59 and exhaust chamber 58. As soon as the ports 54 are uncovered, the pressure on the upper surface of the diaphragm 8 is relieved and the water, as fast as it enters the chamber 9 through port 69, passes out therefrom through ports 54, the lowermost ports 28, channel 24, port 71 and passage 66, into the chamber 16 above the plunger 39. This relief of the pressure on the upper surface of the diaphragm 8, permits the valve 46 to stop in its descent just before it becomes seated and permits sealing water to trickle underneath the same into the bowl to re-fill it while the plunger 39 is descending.

When the plunger 39 reaches its lowermost position, there is no longer any escape for the water entering the chamber 9, and full service pressure is again restored therein and the valve then immediately becomes quietly and firmly seated and all of the parts remain at rest until the handle 79 is again depressed.

The ball and socket joint 43 and the threaded stem 42^a thereof permit adjustments to vary the time of admission of sealing water to the bowl. By this construction, means are provided to adjust the rate 125 of refill of the bowl.

The opening and closing of the flushing device is due solely to the action of hydraulic pressure resulting in the establishment of 130 differences of pressure on opposite sides of

the diaphragm by which back pressure is obtained to an extent causing the various operations to take place.

The flushing device may be readily adjusted to deliver a determined quantity of water at each flushing and consequently is susceptible of use for measuring purposes. While the device dividing chambers 2 and 9 from each other is shown as in the form of a flexible diaphragm it is to be understood that it may be in other forms as, for instance, it may comprise a yieldable member in the form of a piston movable in the body member and serving to divide chamber 2 from chamber 9.

It is to be observed that Figs. 3 and 4 show but one port 28 in the channel 26 while the other channels 24 and 25 are provided with several such ports. This provides for a throttling of the flow through the channel 26 so that the plunger 39 is raised slowly but may fall with comparative rapidity, because of the larger combined area of the ports 28 in the respective channels 24 and 25. This showing is to be taken as merely indicative, because more than one port 28 may be used, or other arrangement may be employed, so long as the capacity thereof is sufficiently small.

30 What is claimed is:

1. A flushing device comprising a hollow body member, a yieldable diaphragm dividing the body into two chambers one of which is provided with a flushing outlet, a valve for the outlet carried by the diaphragm, another chamber associated with that chamber in the body member remote from the outlet, the two associated chambers having connecting and outlet ducts, 40 and a valve structure carried by the yieldable diaphragm and controlling the connecting and outlet ducts.

2. A flushing device comprising a hollow body member, a yieldable member dividing the body member into superposed chambers, one of which has a flushing outlet, means for connection with the service pipe, a valve for the outlet carried by the yieldable member, another chamber carried by and rising 50 from the body member with a passage way between the last named chamber and the higher one of the first two chambers, a valve structure carried by the yieldable member and movable along the passageway, a plunger in the third chamber and movable therewith, ducts connecting the chambers and the passageway and controlled by the valve structure, and means under the control of the plunger in the third chamber for causing the restoration of the parts to the original position after having been operated.

3. A flushing device comprising a hollow body member, and a yieldable member dividing the body member into two superposed chambers, one of which has a flush-

ing outlet, a valve for the outlet carried by the yieldable member, another chamber rising from the body member and separated from the higher one of the superposed chambers by a chambered plug with ports therethrough, a valve structure located in the chambered plug and carried and controlled by the yieldable member for in turn controlling the ports, a piston or plunger in the last named chamber, a valved passageway communicating with the last named chamber and controlled by the plunger, and manually operable means for opening the upper one of the superposed chambers to the flushing outlet for starting the latter into 80 operation.

4. A flushing device comprising a hollow body member, a yieldable member therein separating the interior of the body member into two superposed chambers, one having a water inlet and a flushing outlet, a third chamber above the upper one of the two superposed chambers, with the body member provided with a hollow plug separating the second and third chambers and having a passageway connecting said second and third chambers, ducts in the plug and body member and communicating with a source or supply of water under pressure, a duct connected to the flushing outlet, a manually operable valve controlling the second named duct, a plunger in the third chamber operable by inflow of water to return the last named valve, and a valve structure carried by the yieldable member and movable along the hollow plug to control the flow of water through the ducts.

5. A flushing device for bowls provided with two chambers with a differential valve separating them and controlling the flushing outlet, means for causing the opening of the valve by water pressure, means for causing the return of the valve nearly to closed position, means for checking the closing movement of the valve for an appreciable time in this position, whereby to permit the bowl to re-fill, and means for then causing the valve to settle quietly and firmly on its seat without hammering.

6. A flushing device for bowls provided with two chambers, and a differential valve separating them and controlling the flushing outlet, means for causing the opening of the valve through water pressure, by cutting off the pressure from above the valve, means for restoring pressure to the upper surface of the valve after the flushing operation for causing the return of the valve nearly to closed position, means for relieving the pressure on the upper surface of the valve when the latter is nearly closed and for holding the valve in this position for an appreciable time, whereby to permit the bowl to refill, and means for again restoring the pressure to the upper surface of

the valve to cause the latter to settle quietly and firmly on its seat.

7. A flushing device provided with a differential main valve operable solely by water pressure for controlling the flow of liquid through the outlet, a chamber with a plunger therein for receiving liquid under pressure, a valve structure controlled by the main valve to control the flow of liquid into the chamber to propel the plunger, and means associated with the plunger for controlling the main valve and to restore the parts after the flushing operation.

8. A flushing device for bowls provided with a differential main valve, manually operable means for overcoming the differential condition to cause the valve to open, and means having a slow active travel and operable first to cause the partial closing of the valve after the flushing operation, then to check the valve while water accumulates in the bowl, and then to complete the closing of the valve.

9. A flushing device for bowls provided with a flushing outlet and a differential valve therefor, a chamber connected with the flushing device and provided with means for directing water under pressure into the chamber, a plunger in the chamber controlled by the flow of water under pressure, a valve structure carried by the differential valve and movable therewith to direct water under pressure to the chamber and to drain water therefrom, and valve means for controlling the flow of water from opposite sides of the plunger.

10. A flushing device comprising a hollow body member having two chambers, the lower chamber being provided with an inlet for connection to a service pipe and with an outlet for connection to a toilet bowl, an automatic valve for the outlet forming a partition wall for the chambers, a manually-controlled outlet for evacuating the upper chamber to cause water pressure provided by the service pipe to open the automatic valve, and a third chamber having means associated therewith for so controlling the automatic valve after the flushing operation as to permit the bowl to refill, and to subsequently cause the valve to settle upon its seat.

11. A flushing device comprising a hollow body member with two chambers therein, the lower chamber having an inlet for connection to a service pipe and a flushing outlet for connection to a toilet bowl, a differential valve for the outlet forming a partition wall for the chambers, a manually-controlled outlet connected with the bowl for evacuating the upper chamber to cause the water pressure in the service pipe to open the differential valve, a third chamber having means associated therewith for partially closing the differential valve after the flushing op-

eration and checking it in that position while the bowl re-fills, and then completely closing it.

12. A flushing device comprising a hollow body member having two superposed chambers, the lower chamber having an inlet for connection to a service pipe and a flushing outlet for connection to a toilet bowl, a differential valve for the outlet forming a partition wall between the two chambers, a manually-controlled valve for evacuating the upper chamber to cause service pressure to open the differential valve, a third chamber provided with a plunger reciprocable therein, means for causing the movement of the plunger in one direction during the flushing operation, means under the control of the plunger for stopping the flushing operation, means for causing the return of the plunger and simultaneously the re-fill of the bowl, and means operable when the plunger is restored to its original position to completely close the differential valve.

13. A flushing device comprising a hollow body member having two superposed chambers, the lower chamber being provided with an inlet for connection to a service pipe and an outlet for connection to a toilet bowl, a differential valve for the outlet forming a partition wall between the two chambers, a manually controlled valve for evacuating the upper chamber to cause service pressure to open the differential valve, a third chamber provided with a plunger reciprocable therein, means for causing the movement of the plunger in one direction during the flushing operation, means under the control of the plunger for stopping the flushing operation, means for varying the duration of the flushing operation by adjusting the travel of the plunger, means for causing the return of the plunger and simultaneously the refill of the bowl, and means operable when the plunger is restored to its original position to completely close the differential valve.

14. A flushing device comprising a body member, a yieldable diaphragm dividing the body member into two chambers, the upper one having an outlet adapted to be connected to a toilet bowl, a valve for the outlet carried by the diaphragm, manually-actuated means for cutting off the pressure at the upper side of the valve, whereby to cause the service pressure to raise the valve, a cylindrical chamber containing a plunger, an inlet underneath the plunger opened to service pressure by said manually actuated means and operable to slowly raise the plunger, means limiting the movement of the plunger and actuated by contact with the plunger to restore pressure to the upper side of said valve, and cause the same to settle upon its seat.

15. A flushing device comprising a body

member, a yieldable member in the body member dividing the latter into two chambers, a valve carried by the yieldable member for controlling flow of liquids through and from the flushing device, and a slide valve in one of the chambers and carried by the yieldable member, and means in which the slide valve is mounted for reciprocation and provided with ports and ducts controlled by the slide valve to direct flow of fluid through the flushing device in different directions.

16. A flushing device comprising a body member, a yieldable member in the body member dividing the latter into two chambers with one of the chambers having an outlet leading from the flushing device, a valve for the outlet carried by the yieldable member, a slide valve also carried by the yieldable member, and a plug in which the slide valve is mounted, said body and plug having co-acting ducts and ports whereby to start and continue the operation of the flushing device and then stop the operation within a predetermined time.

17. A flushing device comprising a chamber normally containing water under service pressure, a differential valve normally closing the bottom thereof, an outlet for said chamber, a plunger having a head with means for normally closing the outlet but manually operable to uncover the same to discharge the water from said chamber, a rod having a head in the path of the first-mentioned head and having means to cut off communication between the chamber and service pressure when the plunger is actuated.

18. A flushing device comprising a chamber, a differential valve closing one side thereof, said chamber having an inlet port for connecting it with water under pressure, an outlet for said chamber, a spring-held plunger having a head with means for normally closing the outlet, said plunger being manually depressible in opposition to the spring to uncover the outlet, a friction-held rod having a head in the path of the head of the plunger and having means to cover the inlet port when the plunger is depressed, and pressure-operated means for restoring the rod and uncovering the inlet port after a predetermined time.

19. A flushing device comprising a chamber with an inlet and discharge ports, a friction held rod having a valve movable to close either one of said ports while uncovering the other, manually operable means for moving the rod in one direction, and means operable by water pressure after a predetermined period for returning said rod and valve.

20. A flushing device comprising a chamber with inlet and discharge ports, a friction-held rod having a valve movable to

close either one of said ports while uncovering the other, a head at the lower end of the rod within the chamber, a manually-operable spring-held plunger having a head engageable with the first-mentioned head to move the rod in one direction, and means operable by water pressure after a predetermined period for returning said rod and valve.

21. A flushing device comprising a chamber having a diaphragm for its bottom wall, a differential valve carried by the diaphragm, a neck rising from the chamber, a plug secured in the neck and having a series of circumferential flanges defining annular channels, said plug having a longitudinal bore with ports leading to the respective channels, one of the channels being constantly filled with water under pressure, and another of the channels having a constantly open outlet, and a slide valve in said bore having packing rings, said slide valve being connected with and controlled by the differential valve to control communication through said ports.

22. A flushing device comprising a chamber having a plunger reciprocable therein by water pressure above and below the same, a neck leading from said chamber, a plug secured in the neck and having a series of circumferential flanges defining annular channels, one of the channels being constantly under water pressure, another of said channels being constantly connected with a discharge outlet, said plug having a longitudinal bore with ports leading to the respective channels, and means reciprocable within the bore to establish communication between the channel under pressure and the chamber at either side of the plunger and to simultaneously establish communication between the outlet channel and the chamber on the other side of the plunger.

23. A flushing device comprising a chamber having a plunger reciprocable therein by water pressure above and below the same, a plug at one end of the chamber and having a longitudinal bore, a slideable valve in said bore having means associated therewith and actuated by water pressure to admit pressure to one end of the chamber and to simultaneously open the other end of the chamber to an outlet, and means actuated by the plunger as it approaches the other end of the chamber to reverse the position of the slideable valve and thereby reverse the pressure and outlet connections to the ends of the chamber and to return the plunger.

24. A flushing device comprising an upper and lower chamber with a differential valve forming a partition therebetween, both chambers being normally under pressure, an outlet chamber having a constant connection with a discharge pipe, a hollow guide having ports leading to the outlet chamber, a

spring-held plunger reciprocably mounted in said guide and having channels leading from said ports to the upper one of said first-mentioned chambers, means on said 5 plunger normally closing said channels, said plunger being manually-operable to open said channels and vent the upper chamber through the outlet chamber, and means simultaneously operated by the plunger for 10 cutting off pressure from said upper chamber.

25. A flushing device comprising an upper and a lower chamber with a differential valve forming a partition therebetween, both 15 chambers being normally under pressure, an outlet chamber having constant connection with a discharge pipe, a hollow guide having ports leading to the outlet chamber, a spring-held plunger reciprocably mounted in said 20 guide and having channels leading to said ports from the upper one of said first-mentioned chambers, means on said plunger for normally closing said channels, said plunger being manually operable to momentarily 25 open said channels and partially vent the upper chamber into the outlet chamber, means simultaneously operated by the plunger 30 for cutting off pressure from the upper chamber, and automatic pressure-operated for means completing the venting of the upper chamber.

26. A flushing valve comprising a hollow body member, a yieldable member dividing the body member into superposed chambers, 35 one of which has a flushing outlet, means for connecting with the service pipe, a valve for the outlet carried by the yieldable member, a third chamber carried by and rising from the body member, a passage between 40 the third chamber and the higher one of the first two chambers, a vertically movable valve in the passage, a valve structure carried by the yieldable member and movable in the third chamber, a plunger movable 45 in the third chamber above the valve structure, ducts connecting the chambers and the passage and controlled in part by the valve structure and in part by the valve in the passage, a manually operable plunger adapted 50 when actuated to move the valve in the passage, an outlet chamber communicating with the third chamber, a duct leading from the third chamber to the lower one of the 55 said superposed chambers, and another duct leading from the flush bowl to the said outlet chamber.

27. A flushing valve comprising a hollow body member, a yieldable member dividing the body member into superposed chambers, one of which has a flushing outlet, means 60 for connection with the service pipe, a valve for the outlet carried by the yieldable member, a third chamber arranged vertically and carried by the body member, a passage between the third chamber and the higher one of the first two chambers, a vertically movable valve in the 65 passage, a valve structure carried by the yieldable member and movable in the third chamber, a plunger also movable in the third chamber above the valve structure, an outlet chamber having a duct leading to the third chamber, another duct leading from the outlet chamber to the flush bowl, a manually 70 operable plunger adapted when actuated to move the vertically movable valve in the passage, a duct leading from the third chamber to the lower one of the superposed chambers, said outlet chamber being controlled by the manually operable plunger to 75 place the upper one of the superposed chambers into communication with the outlet chamber.

28. A flushing device comprising a body member, a yieldable member in the body member dividing the latter into two superposed chambers, a valve carried by the yieldable member for controlling the flow of liquids through the flushing outlet, a slide valve in one of the chambers and connected 90 to and carried by the yieldable member, and adjustable means between the slide valve and the yieldable member to vary the time of admission of sealing water to the bowl.

29. A flushing device comprising a chamber with inlet and discharge ports, a friction held rod having a valve movable to close either one of said ports while uncovering the other but normally closing the discharge port, manually operable means for moving said rod to uncover the discharge port, a second chamber containing a reciprocable plunger, an inlet underneath the plunger, means actuated by the closing of the inlet to the first-mentioned chamber to 95 open the inlet to the second chamber, and means in the path of said plunger and operated thereby to restore said rod to its original position.

In testimony that I claim the foregoing as 110 my own, I have hereto affixed my signature.

THOMAS ROBERT BEGGS.
